DESIGN FOR A REFRIGERATOR CABINET

Donald E. Dailey, Bryn Mawr, Pa., assignor, by
mesne assignments, to Philco Corporation,
Philadelphia, Pa., a corporation of Pennsyl-
vania

Application March 16, 1946, Serial No. 127,599

Term of patent 7 years

(Cl. D67—2)

To all whom it may concern:

Be it known that I, Donald E. Dailey, a citizen
of the United States, residing at Bryn Mawr, in
the county of Montgomery and State of Pennsyl-
vania, have invented a new, original, and orna-
mental Design for a Refrigerator Cabinet, of
which the following is a specification, reference
being had to the accompanying drawing, forming
part thereof, in which:

Figure 1 is a view in perspective of a refrig-
erator cabinet, showing my new design; and

Figure 2 is an enlarged sectional view, taken
along the line 2—2 of Figure 1.

The side of the cabinet not disclosed in the
drawing is substantially plain and similar to the
side shown.

I claim:
The ornamental design for a refrigerator cabi-
net, substantially as shown and described.

DONALD E. DAILEY.
